UNITED STATES PATENT OFFICE.

PHILIP JOHN WALSH, OF SAN FRANCISCO, CALIFORNIA.

RADIO RECEIVING SYSTEM.

Application filed February 23, 1926. Serial No. 89,976.

This invention relates to a system for receiving and amplifying high frequency electrical impulses, such for example as radio signals.

5 In my Patent No. 1,594,582, issued August 3, 1926, and entitled "Amplifier system", I describe a scheme in which several thermionic vacuum tubes are utilized, each having a control electrode and a positive electrode 10 or plate, in addition to the filament that serves as the source of electrons. I explain in that application, the advantages secured by providing a source of constant direct current for impressing a positive voltage upon 15 the plate as regards the filament, which plates are arranged in parallel; and I further disclose a scheme whereby the amplifying effect of the two tubes can be built up and greatly increased.

20 In the present application, I shall describe several further forms of the invention, based upon substantially the same fundamental principles; and it is accordingly one of the 25 objects of my invention to provide a high degree of amplification with relatively few tubes.

It is still another object of my invention to make it possible to secure this degree of amplification without creating instability in the 30 circuits.

My invention possesses many other advantages, and has other objects which may be made more easily apparent from a consideration of several embodiments of my invention. 35 For this purpose I have shown a few forms in the drawings accompanying and forming part of the present specification. I shall now proceed to describe these forms in detail, which illustrate the general principles 40 of my invention; but it is to be understood that this detailed description is not to be taken in a limiting sense, since the scope of my invention is best defined by the appended claims.

45 Referring to the drawings:

Figure 1 is a schematic wiring diagram of one form of my invention; and

Fig. 2 is a diagram of a modification thereof.

50 In Fig. 1, there is shown an absorbing circuit, such as elevated conductors 11, loading coil 12, and a ground connection 13. In the present instance, there is inductively coupled to coil 12, a tunable circuit 14, comprising a 55 coil 15 in inductive relation with coil 12,

and a variable condenser 16. As is well understood, upon proper tuning as by adjustment of condenser 16, a maximum E. M. F. can be secured for the particular frequency received, across the terminals of the 60 condenser 16, or of coil 15. This E. M. F. is caused to affect an electronic emission device 17 directly.

This device includes a heated filament 18, from which electrons are attracted to a plate 65 19, kept at a potential positive with respect to the filament in order to attract the electrons. It is well-known that the "space current" between the plate and filament can be varied by a comparatively large amount by 70 the aid of a control electrode 20, such as a grid, interposed between the plate and filament, and controlling the potential of a point between these two electrodes. It is this theory upon which the amplification by such 75 tubes is based. In order to provide the proper potential differences between the filament 18 and grid 20, these two electrodes are accordingly connected to opposite terminals of the condenser 16. The circuit thus 80 formed between these electrodes can be aptly termed the input circuit. In order to heat filament 18, it is connected, through a variable resistance 21, with a source of electrical energy, such as a portion of the battery 22. 85 Connections 23 and 24 serve as the links between the filament and this battery.

Due to the fluctuations in potential between grid 20 and filament 18 when the apparatus is receiving signals, corresponding 90 magnified fluctuations in the space current are produced. The output circuit in which this space current path is present, however, is so arranged that the fluctuations therein are not allowed to affect the source of positive potential for the plate 19, but instead, 95 a further tube 25 is influenced thereby. Broadly this is accomplished in a manner set forth in my prior application. Thus the output circuit for tube 17 can be traced from 100 the lower positive terminal of battery 22, connection 26, coils 27 and 28, variable tap 29 on a resistor 30, through a portion of said resistor, coil 31, plate 19, back to filament 18, and by way of connection 23, to the 105 other terminal of battery 22. The coil 27 can be an iron cored coil, forming with coil 28, an effective radio frequency choke, of such value that the supply of direct current in the path just traced is maintained constant. 110

The space current fluctuations must therefore find another path distinct from the battery 22. This is accomplished by connecting, in parallel with the output circuit of tube 5 17, the output circuit of the tube 25. This tube has a filament 32 also heated from battery 22, as well as the plate electrode 33. The output circuit can therefore be traced in common with that of tube 17, up to tap 10 29, where it continues through a portion of resistor 30, coil 33' in close inductive relation with coil 31 and opposed thereto, plate 33, filament 32, back to battery 22. It is thus seen that whatever fluctuations may be set 15 up in the space current of tube 17 causes equal and opposite fluctuations in the space current of tube 25, for the sum of these space currents must be constant, due to the constancy of the current from source 26.

20 The tap 29 and resistor 30 are provided in order to adjust the relative impedance of the two space current paths, whereby exact neutralization can be effected between coils 25 31 and 33 when no signals exist, and therefore, no fluctuations in the space current of tube 17. Resistor 30 can be of the order of 200 ohms.

It is further evident that the magnetic effect of coils 31 and 33' is zero when no 30 signals are received, but when received, the departure from exact neutralization is exactly twice as much as that which would have been produced by the fluctuations in tube 17 alone. All this has been described 35 and claimed in the prior application referred to.

The input circuit of tube 25 is arranged 40 to be affected by this magnetic unbalance between coils 31 and 33', whereby large variations in the impedance through tube 25 are also secured, in a sense such as to augment the effect of the variations in tube 17. For this purpose, there is a coil 34, coupled to 45 coils 31 and 33', in which is induced an E. M. F. in accordance with the variations in the unbalanced currents flowing in these coils. In order to tune the oscillations thus set up, a variable condenser 35 is connected 50 across coil 34. One terminal of coil 34 is connected, as by lead 36, with the grid 37 of tube 25. To complete the input circuit for this tube, I utilize a rectifying arrangement 55 for the impulses in coil 34. This assists not only in stabilizing the system, but also serves to detect the signal.

The rectifier arrangement in this instance is shown as a tube 38, connected between the other terminal of coil 34 and filament 32. This tube is preferably a "soft" tube, having 60 some gas content. It has a filament 39, fed as the other filaments so far described, and a plate 40 to which coil 34 is connected. In order to control the conductivity of the path through this tube 38, the grid 41 thereof is connected to the filament 39 by way of

the coil 42, and a variable resistance 43, bridged by a battery 44 having its negative terminal connected to the grid 41.

It is evident that only those half-cycles of current can pass through tube 38 which 70 make the lower terminal or coil 34 positive; therefore there is a rectifying effect, and grid 37 can be only negatively charged—never positively—because it is connected to the upper terminal of coil 34, which is negative when the lower terminal is positive. The rectified current through tube 38 finds a return path through high resistance 45 to upper terminal of coil 34.

The imposition of a negative charge on 80 grid 37 of a value dependent upon the degree of unbalance of coils 31 and 33', serves to accentuate this unbalance, and therefore coil 34 responding thereto, can be taken as forming the output circuit 85 for the system thus far explained. But before describing how this coil affects the succeeding stages, it is advantageous to consider in greater detail the operation of the system thus far set forth. Of course the 90 diagram is purely schematic; coils 12 and 15 can be toroidal, and may be variably coupled together; coils 31, 33', and 34 can be either toroidal or honeycombed, or any other kind of high frequency coil. Furthermore, the 95 negative terminals of all of the filaments can be grounded as is sometimes done, and is indicated at 46. These refinements however, are of course not absolutely essential.

The stabilizing effect of the rectifier tube 100 38 can be controlled in several ways. For example, the tap on resistance 43 can be varied, to vary the potential difference between the grid and filament thereof; or the resistance in the circuit of filament 39 can be varied. In either manner, the effective impedance of the tube can be adjusted. For receiving long wave signals, the filament 39 can be heated to a higher degree without danger of 105 instability; while short wave signals require a reduced heating. Similarly, if the negative bias system is used for controlling the action of tube 38, then the tap on resistance 43 must be adjusted to give a larger negative bias to the grid when shorter wave 110 lengths are received.

Since only the rectified half-waves are 115 allowed to affect the grid circuit of tube 25, and since the degree to which this grid circuit is affected can be easily controlled, it is evident that it is a simple matter to produce stable operation without the production of parasitic oscillations. The rectification also 120 serves as detection; therefore it is necessary merely to connect succeeding amplifier stages across an element in the circuit in which only the half-wave currents can exist. Such an element is the resistance 45, across the terminals of which, an audio frequency amplifier 125 tube 46 can be connected.

This tube has an input circuit, including filament 47 and grid 48 connecting across the resistance 45, and operating in a well-known manner to cause amplified fluctuations in the space current between filament 47 and the positive or plate electrode 49. This tube 46 is paired with another tube 50, similarly to the arrangement of tubes 25 and 17, whereby fluctuations in tube 46 are caused to produce opposite fluctuations in tube 50. For this purpose, provisions are again made to ensure constant current flow through the source supplying the output circuits of both tubes. Thus battery 22 has connected in series there- 15 with an impedance 51, between the positive terminal of the battery and a tap 52, where the current divides and passes through both the output circuits of tubes 46 and 50.

The output circuit of tube 46 includes a portion of balancing resistor 53, a coil 54, plate 49, filament 47, back to the negative terminal of battery 22. Similarly, the output circuit of tube 50 includes a portion of resistor 53, coil 55, bucking coil 54 and on the same iron core 56 therewith, plate 57 of tube 50, filament 58 thereof, back to the negative terminal of battery 22. The core 56 can be used to advantage, because now audio frequency currents are used. This core has a limb 59 on which coil 60 is placed, which is thus responsive to the unbalance in the magnetism produced by coils 54 and 55. This unbalance is in turn used to affect the space current of tube 50, by being connected between the filament 58 and grid 61 thereof. The building up of a magnetic field in the core 56 by the difference in the output circuits is controlled by the aid of a movable armature 62 placed in a gap in the magnetic circuit of core 56 and leg 59.

The telephone 63 is shown as inductively coupled with coils 54 and 55, by the aid of coil 64 wound on another leg 65 of core 56. This telephone carries the amplified audio frequency currents which are induced due to the varying unbalance between coils 54 and 55, accentuated by the effect of the grid circuit control of coil 60.

The tubes 17 and 25 and the associated circuits can be designated as a radio frequency system; while tubes 46 and 50 and the associated circuits can be designated as an audio frequency system; the tube 38 serves as a detector. It would of course be possible to multiply such systems indefinitely by proper cascade connections. In Fig. 2, however, I disclose a further scheme for providing a succession of amplification effects.

In this figure, merely for the sake of illustrating the various forms my invention may take, I show a loop absorbing circuit, including a loop 66 having a tuning condenser 67 in series therewith. As before, the input electrodes 68 and 69 of an amplifier

70 are connected respectively across the terminals of the condenser 67, whereby the space current therethrough is varied. The battery 71 serves as the source of electrical energy for the output circuit for tube 70, the current flow therefrom being maintained constant as in the earlier forms, as by the aid of the iron-cored impedance coil 73.

The output circuit for tube 70 can be traced from the positive terminal of battery 71, coil 73, coil 74, plate 75, filament 68, back to the negative terminal. Closely coupled with coil 74 is an opposing coil 78 which is fed from the same constant current source. Its circuit may be traced as follows: from the positive terminal of battery 71, coil 73, coil 78, adjustable resistance 79, back to the negative terminal. It is evident that in this form of the invention, the opposed coil 78 is not in circuit with any vacuum tube; instead, a resistance 79 is provided to set the current flow at such value through this coil as exactly to neutralize coil 74 when no signals are received.

When signals are received, the current in coil 74 of course fluctuates, and since the current through coil 73 is constant, there is an equal and opposite fluctuation in the current in coil 78. The result is that an E. M. F. is induced in a coil 80, coupled to coils 74 and 78, and tuned by a variable condenser 81. Since the fluctuations in E. M. F. in this coil are much larger than in either coil 74 or 78, the advantages of my system are apparent. These fluctuations can in turn be impressed upon the input circuit of a succeeding amplifier tube 72, having a filament 76, a plate 77, and a grid 82. The output circuit of this tube can in turn be connected in a manner entirely similar to that of tube 70: through a coil 83 maintaining the current from source 71 constant, and through coil 84 which is opposed by the coil 85 in a circuit branching the output circuit. The effects being identical with those already described, it is considered unnecessary to detail them further.

While of course it is possible to extend the system to include as many tubes such as 70 and 72 in cascade, yet I show the succeeding tubes 86 and 87, which are influenced by the coil 88 coupled to coils 84 and 85, as forming a detecting system. For this purpose, tube 86 is a two-electrode rectifier tube, having a filament 89 and a plate 90. This plate is connected to one terminal of coil 88, the other terminal being connected to grid 91 of tube 87. By controlling the filament temperatures for this tube, it is possible as before, to adjust the effect of the coil 88. It is thus seen that only during half-cycles is the input circuit of tube 87 connected to the coil 88, due to the unidirectional characteristic of tube 86. The input circuit can be traced as follows: from

grid 91, coil 88, plate 90, filament 89, to filament 92 of tube 87. A high resistance 93 of the order of one or two megohms bridges the input electrodes 92 and 91 to permit the current to flow back to the coil 88 during the active half-cycles.

The tube 87 in turn can be used to affect in succession one or more audio frequency amplifiers 94, 95. These may be connected in 10 a manner entirely similar to that already described; the only difference being that iron cored coil arrangements 96 and 97 can be used for coupling the successive stages, since now audio frequency currents are dealt 15 with. The last tube 95 has an output circuit that includes the phones 98 or other translating device.

It is evident that modifications of the coil arrangements could be utilized. Preferably 20 toroid coils are used for such as 74, 78 and 80. Furthermore, types of detectors other than those shown in the two forms could be substituted, such as the well-known grid condenser and leak arrangement.

25 I claim:

1. In combination, a source of constant direct current, means forming a pair of paths in parallel supplied by said source, means responsive to signaling impulses for 30 varying the impedance of one of the paths, means whereby the currents in the two paths are oppositely varied while leaving their sum constant, a circuit coupled to both paths to cause it to respond to the variations in current flow therein, said circuit further influencing one of said paths to accentuate the difference in impedance of the two paths, and an adjustable rectifying device associated with said circuit for controlling the effect of said circuit on the paths.

2. In combination, a source of constant direct current, means forming a pair of paths in parallel supplied by said source, means responsive to signaling impulses for 45 varying the impedance of one only of the paths, means whereby the currents in the two paths are oppositely varied, a circuit coupled to both paths to cause it to respond to the variations in current flow therein, and means for adjusting the current flow in 50 said circuit.

3. In combination, a source of constant direct current, means forming a pair of paths in parallel supplied by said source, 55 means responsive to signaling impulses for varying the impedance of one only of the paths, means whereby the currents in the two paths are oppositely varied, a circuit coupled to both paths to cause it to respond to the variations in current flow therein, and an adjustable rectifying device associated with said circuit for controlling the current flow therein.

4. In combination, a source of constant 60 direct current, means forming a pair of

paths in parallel supplied by said source, means responsive to signaling impulses for varying the impedance of one of the paths, means whereby the currents in the two paths are oppositely varied while leaving their 70 sum constant, a circuit coupled to both paths to cause it to respond to the variations in current flow therein, means whereby said circuit influences the impedance of one of the paths to accentuate the difference in 75 current flow, and an amplifier conductively connected to said circuit.

5. In combination, a source of constant direct current, means forming a pair of paths in parallel supplied by said source, means 80 responsive to signaling impulses for varying the impedance of one of the paths, means whereby the currents in the two paths are oppositely varied while leaving their sum constant, a circuit coupled to both paths to 85 cause it to respond to the variations in current flow therein, and means, comprising resistances in the paths, for adjusting the impedances thereof.

6. In combination, a source of constant 90 direct current, an electronic emission device having its space current supplied by said source, means for varying the impedance of said device in response to received impulses, means forming a path fed from said source 95 in parallel with said device, means whereby the impedance of said path is influenced by said device and not by the received impulses, a pair of opposed coils, one in each path, for producing a combined magnetic effect 100 equivalent to the difference in current flow in the two paths, a resistor connecting the two coils, and a variable tap on said resistor connecting to the source, for adjusting the relative effects of the coils.

7. In combination, a source of constant direct current, a pair of electronic emission devices having their space currents supplied by said source, means for varying the impedance of one of said devices in response 110 to received impulses, a circuit responsive to the difference in the space currents, and influencing the impedance of the other of said devices, and means for adjusting the effect of said circuit, comprising an electronic 115 emission device having means for adjusting its impedance, and placed in said circuit.

8. In combination, a source of constant direct current, a pair of paths supplied in parallel from said source, means for varying the impedance of one only of said paths in response to received impulses, a pair of coils, one in each path, a core on which said coils are placed in opposed relation, means responsive to the combined magnetic effect of 120 said coils, and means for varying the reluctance of the core.

9. In combination, a source of constant direct current, a pair of paths supplied in parallel from said source, means for varying 125

- the impedance of one of said paths in response to received impulses, a pair of coils, one in each path, a core on which said coils are placed in opposed relation, means whereby the combined magnetic effect of the coils is utilized to vary the impedance of the other path in order to accentuate the difference, and means for varying the reluctance of the core.
- 10 10. In combination, a source of constant direct current, a pair of electronic emission devices, the space currents of which are supplied from said source, means for varying the impedance of one of said devices in response to received impulses, a pair of coils, one in circuit with each path, a core on which said coils are placed in opposed relation, means whereby the combined magnetic effect of the coils is utilized to vary the impedance
- of the other device in order to accentuate 20 the difference in current flow, and means for varying the reluctance of the core.
11. In combination, a source of constant direct current, means forming a pair of paths in parallel supplied by said source, 25 means responsive to signaling impulses for varying the impedance of one of the paths, means whereby the currents in the two paths are oppositely varied while leaving their sum constant, a circuit coupled to both paths 30 to cause it to respond to the variations in current flow therein, and means for adjusting the impedance of at least one of said paths.
- In testimony whereof I have hereunto set 35 my hand.

PHILIP JOHN WALSH.
